CLAIM

I claim the ornamental design for a playing field, as shown and described.

DESCRIPTION

FIG. 1 is a perspective view of a playing field showing my new design.

FIG. 2 is a top plan view of the playing field; and,
 FIG. 3 is a right side view of the playing field, the left side view, front view, and rear view being identical to the right side view.

1 Claim, 3 Drawing Sheets(56)
